HEAVY-DUTY ELECTRODE HOLDER

Norman A. Birch, Mahwah, N. J.

Application August 18, 1945, Serial No. 611,437

2 Claims. (Cl. 219—8)

(Granted under the act of March 3, 1883, as
amended April 30, 1928; 370 O. G. 757)

1

The invention described herein may be manufactured and used by or for the Government for governmental purposes without the payment to me of any royalty thereon.

This invention relates to a heavy duty electrode holder designed for use with currents of the order of 500 amperes or more. In the manufacture of certain ordnance items, welding operations require heavy currents if production at a desired rate is to be maintained. In using holders heretofore available, considerable trouble has been experienced when employing currents greater than 300 amperes owing to the heating of the holders which greatly shortened the life thereof and required frequent replacements. It is an object of the present invention to provide an electrode holder so designed as to reduce heating therein to a minimum. It is a further object of the invention to provide a holder which is light in weight so that undue fatigue of the operator is avoided. It is another object of the invention to provide a holder the electrode gripping mechanism of which can be manipulated by one hand to facilitate the insertion of electrodes and the removal of residue ends thereof. According to the present invention an electrode holder is provided having the above-mentioned qualities as well as mechanical simplicity and ruggedness. For a more complete understanding of the invention, reference may be had to the following description of an embodiment thereof and to the drawing of which:

Figure 1 is a side elevation of an electrode holder embodying the invention.

Figure 2 is a sectional view of the same on a vertical longitudinal plane.

Figure 3 is a sectional view of the conducting handle member.

Figure 4 is an end elevation of the conducting sleeve.

The electrode holder illustrated in the drawing comprises a cylindrical handle member 10 of low-resistance metal such as brass or copper having a bore 12 in the rear end thereof to receive the end of an insulated electric cable 14 by which current is supplied to the electrode. The skinned end of this cable is preferably soldered into the bore 12 to provide a good electrical connection which will carry heavy currents without excessive heating. For the same reason the wall of the member 10 around the bore 12 is preferably of considerable thickness. The member 10 also has a bore 16 extending in from its forward end, the outer end portion of this bore being screw-threaded as at 18 for threaded engagement with

2

the rear end portion of a tubular sleeve 20 of copper or other low-resistance metal. The area of contact between the thread faces of the sleeve 20 and the handle member 10 is considerable and these faces are strongly pressed together so that undue heating at the threaded joint is avoided. When the sleeve 20 is assembled with the member 10, a flange 22 on the sleeve and the forward end of the member 10 grip between them a spatter shield which comprises a radially extending disc 24 of insulating fibre material reinforced by washers 26 and 28 on its opposite faces.

Slidable in the sleeve 20 is a pusher rod or plunger 30 which is of substantially smaller diameter than the interior diameter of the sleeve 20. This plunger is provided with a transverse V notch 32 at its forward end, the trough of the V being aligned with a pair of holes 34 through the walls of the sleeve 20 which are adapted to receive an electrode. For the insertion of an electrode the plunger 30 must be retracted sufficiently to clear the holes 34. After the electrode has been inserted through the holes 34 the plunger 30 is pressed forward so that its outer or forward end engages the electrode in the notch 32 and presses it firmly against the side edges of the holes 34 so that good electrical contact is had between the sleeve 20 and the electrode. In order to maintain firm pressure between the electrode 30 and the edges of the holes 34, a helical spring 36 is seated in the bore 16 of the handle member 10, the forward end of this spring bearing against an enlarged end portion 38 of the plunger 30. A bolt 40 extends through a transverse bore in the rear end portion 38 of the plunger 30 and also through a pair of aligned slots 42 in the walls of the member 10. These slots afford limited longitudinal movement of the plunger 30 to enable the forward end thereof to clear the holes 34.

For the retraction of the plunger 30 a cam lever 44 is provided. This may be made of a single piece of heavy sheet steel cut to shape and bent to form a pair of parallel elements having cam edges 45 bearing against the washer 26 of the shield. The cam lever 44 has an extension 46 which serves as a grip and is adjacent to the handle 10 so that the handle and grip can be grasped by one hand of the operator and may be squeezed to retract the plunger 30. This leaves the other hand of the operator free to insert or remove an electrode. The parallel elements of the cam lever are provided with aligned holes through which the bolt 40 extends so that this bolt acts as a pivot pin for the cam lever 44. For the protection of the operator's hands the

grip portion 46 of the cam lever is preferably tapered. The brass handle member 10 is surrounded by insulation in the form of a fibre jacket or casing 50 which is preferably provided with a number of ventilation holes 52, a pair of diametrically aligned slots which register with the slots 42 in the wall of the member 10, a slot 54 in the forward end for the purpose hereinafter described, and a hole opposite the slot 54 which registers with a hole 56 through the threaded portion of the wall of the member 10. The hole 56 is adapted to receive an Allen screw 58 which enters a recess or hole in the rear end portion of the sleeve 20 to lock the sleeve in its assembled relation with the member 10. It is necessary to prevent relative angular movement between the sleeve 20 and the member 10 and also between the plunger 30 and the member 10 so that the holes 34 in the sleeve will be maintained in alignment with the end groove 32 in the plunger. The pivot pin 40 serves to prevent relative angular movement between the plunger 30 and the member 10.

Opposite the set screw 58 a coupling assembly 60 for an air supply pipe line 62 is inserted through the slot 54 of the insulating sheath 50 and secured in a hole 64 in the member 10 which registers with a hole 66 through the sleeve 20 to admit air or other coolant from the pipe 62 into the interior of the sleeve 20. The use of an air stream may not be necessary when relatively low amperages are employed but will usually be found desirable when high amperages of the order of 500 or more are employed. The stream of air entering the interior of the tool through the pipe 62 and the hole 66 is divided, a portion flowing out through the slots 42 which are to the rear of the hole 66, the rest of the air stream flowing forward in the clearance between the sleeve 20 and the plunger 30 and escaping through the holes 34, the diameter of the holes 34 being substantially larger than the electrode itself. In order to maintain a uniform clearance between the sleeve and the plunger, the latter may be provided with four lugs 70 near the forward end thereof, the extreme diameter of the plunger through these lugs being slightly less than the interior diameter of the sleeve 20. The air stream flowing out through the holes 34 thus provides a counter current cooling stream which prevents excessive heat flow from the electrical end of the tool to the handle thereof.

The forward end of the tube 20 is closed by a copper plug 72 which is driven into the end of the tube and is brazed therein. This plug is centrally drilled and tapped to receive a screw 74 by which a fibre insulating cap 76 is secured to the forward end of the tool so as to avoid undesirable short circuit contacts between live elements of the tool and metal objects near the work.

I claim:

1. An electrode holder comprising a tubular sleeve of low-resistance metal having holes near its outer end to receive an electrode transversely therethrough, a handle member of low resistance metal secured to the inner end of said sleeve with a good electrical connection, an insulating sheath surrounding said handle member, a shield extending radially from said sleeve at the forward end of said handle member, a plunger slidable in said sleeve to press against an electrode extending through said holes, a spring seated in said handle member and pressing against the inner end of said plunger, and means operable by one hand to retract said plunger, said last mentioned means including a cam lever pivotally secured to said plunger near the inner end thereof, one end portion of said lever being a grip element extending adjacent to said handle member and adapted to be manually pressed toward said handle to rock the lever on its pivot, the other end portion of said lever being a cam element movable against said shield by rocking of the lever to force said pivot and plunger rearward.
2. An electrode holder comprising a metal handle member having a bore extending into its forward end, a tubular metal sleeve screw-threaded into the forward portion of said bore, a spring seated in said bore, a plunger slidable in said sleeve having an enlarged rear end portion pressed by said spring against the rear end of said sleeve, a pivot pin passing transversely through said enlarged portion of the plunger and the walls of said handle member, said handle member having aligned longitudinal slots in opposite walls thereof for said pin whereby limited movement of said pin in the direction of the axis of the handle member is permitted, a radial shield surrounding the sleeve at the forward end of the handle member, and a cam lever rockably mounted on said pin, said lever having a cam portion bearing on said shield and adapted to force said pin rearward when the lever is rocked.
